(57) **CLAIM**

The ornamental design for a combined workout and storage bench, as shown and described.

DESCRIPTION

FIG. 1 is a front left perspective view of the combined workout and storage bench showing our new design; FIG. 2 is a rear left perspective view of FIG. 1; FIG. 3 is a front elevational view of FIG. 1; FIG. 4 is a rear elevational view of FIG. 1; FIG. 5 is a left-side elevational view of FIG. 1, the right-side elevational view being a mirror image thereof; FIG. 6 is a perspective right view of FIG. 1; FIG. 7 is a top plan view of FIG. 1; FIG. 8 is a bottom plan view of FIG. 1; FIG. 9 is a front left perspective view thereof, illustrated with the bench portion in a raised position; FIG. 10 is a rear perspective view of FIG. 9; FIG. 11 is a left-side elevational view of FIG. 9; and, FIG. 12 is a rear elevational view of FIG. 9. The dumbbells shown in broken lines in FIGS. 1, 6 and 9 are for the purpose of illustrating environmental structure which form no part of the claimed design. The remaining broken lines shown in drawings are for the purpose of illustrating portions of the combined workout and storage bench, which form no part of the claimed design.

1 Claim, 9 Drawing Sheets
